DESIGN FOR A BROOM

Gottlieb John Kreissler, Sedalia, Mo.

Application December 8, 1937, Serial No. 73,465

Term of patent 14 years

To all whom it may concern:

Be it known that I, Gottlieb John Kreissler, a citizen of the United States, residing at Sedalia, in the county of Pettis and State of Missouri, have invented a new, original, and ornamental Design for a Broom, of which the following is a specification, reference being had to the accompanying drawing, forming part thereof.

In the drawing:

Fig. 1 is a front elevational view of a broom, showing my new design, a portion of the handle being shown as broken away for convenience in illustrating the design.

Fig. 2 is a side elevational view thereof with the portion of the handle broken away for convenience of illustration.

The present application is a continuation in part of applicant's prior design application Serial No. 70,767.

I claim:

The ornamental design for a broom, as shown and described.

GOTTLIEB JOHN KREISSLER.
